UNITED STATES PATENT OFFICE.

MICHAEL RIEGLER, OF UNTERKOCHEN, NEAR AALEN, GERMANY, ASSIGNOR OF ONE-HALF TO LOUIS SCHOPPER, OF LEIPZIG, GERMANY.

METHOD AND MEANS FOR TESTING PAPER-PULP.

1,193,613.

Specification of Letters Patent. Patented Aug. 8, 1916.

Application filed September 8, 1913. Serial No. 788,674.

To all whom it may concern:

Be it known that I, MICHAEL RIEGLER, a subject of the Austro-Hungarian Emperor, residing at Unterkochen, near Aalen, 5 Wurttemberg, in Germany, have invented certain new and useful Improvements in Methods and Means for Testing Paper-Pulp, of which the following is a specification.

The invention relates to a method of, and 10 apparatus for, testing paper-pulp at that stage of manufacture when it is withdrawn from the rag-engine, the character of the paper-pulp determining the kind of paper to be produced.

15 The method consists in pouring a certain quantity of the pulp to be tested into a container provided with a sieve, from which the water flows, more or less rapidly, into another container and thence into two separate collecting vessels, the variations in the quantity of water in the latter vessels determining the quality of the paper pulp.

20 Two suitable forms of apparatus for carrying the invention into effect are shown in 25 the accompanying drawing, in which:—

Figure 1 is a side view, and Fig. 2 a front view partly in section of one form of apparatus, and Fig. 3 a side view partly in section of a modified form of apparatus.

30 The apparatus comprises a hopper *a* provided with a detachable sieve *b*. The pulp is poured into the hopper *a* so that the water is separated from the fibrous matter, and drips more or less rapidly through the sieve 35 *b* according to the character of the pulp, into the container *c*. The said container has two outlets *d* and *e*, disposed at different levels and act in such manner that with slow percolation the water only flows out 40 of the lower outlet *d* which is of small cross section, whereas with a rapid percolation only a part of the water is able to escape through the small opening *d*, the remainder passing off through the larger opening *e*. The water 45 flows through the outlets *d* and *e* into separate collecting containers *f* and *g*, from which it is removed for measurement, so that the quality of the pulp can be determined.

50 The two forms of apparatus shown in the drawing only differ in shape, the container *c* in Figs. 1 and 2 being in the form of a trough with its base inclined in one direction, whereas the apparatus shown at Fig. 3

is in the form of a cylinder, the funnel 55 shaped lower part of which is provided with a discharge pipe *r* branching off at *e*. The action is the same with both forms of apparatus. To enable the position of the whole apparatus to be correctly adjusted a pendulum *h* is preferably provided.

What I claim as my invention and desire to secure by Letters Patent of the United States is:—

1: An apparatus for testing paper pulp, 65 comprising a hopper, a perforated bottom therefor, a container in communication with the hopper, a plurality of outlets arranged in the bottom wall of the container at different heights, and independent means for collecting the constituents passing from each of the outlets in the bottom wall of the container.

2. The method of testing paper pulp consisting in collecting a quantity of pulp, 75 draining off the water from said pulp into a receptacle having openings arranged at different heights and discharging into independent collecting vessels, the variations of the quantity of water in the vessels determining the quality of the pulp.

3. An apparatus for testing paper pulp comprising a hopper for the reception of the pulp, a perforated bottom for said hopper, a container in communication with the 85 hopper having a plurality of outlets passing through the walls thereof at different heights, and a collecting means in communication with said outlets.

4. An apparatus for testing paper pulp 90 comprising a hopper, a container below said hopper having a plurality of constantly opened outlets at different heights arranged within the wall of the retainer, and separate collecting means in communication 95 with said outlets.

5. An apparatus for testing paper pulp comprising a hopper, a perforated bottom therefor, a container having an inclined wall in communication with the hopper, a 100 plurality of outlets arranged in the inclined wall of the container at different heights, and a collecting vessel in communication with each of said outlets.

6. An apparatus for testing paper pulp 105 comprising a hopper, a perforated bottom therefor, a container below said hopper having two constantly opened outlets ar-

ranged therein at different heights, and an independent collecting vessel for each outlet.

7. An apparatus for testing paper pulp comprising a feeding hopper, a container below said hopper and in communication therewith provided with a plurality of outlets in the walls thereof arranged at different heights, the outlet openings being constantly opened and having unobstructed

passages therethrough and collecting means arranged below said outlets.

In testimony whereof I have signed this specification in the presence of two witnesses.

MICHAEL RIEGLER.
